DESIGN FOR A JUVENILE SWING

William I. Smith, Goshen, Ind., assignor to The
Hetrick Manufacturing Company, Toledo,
Ohio, a corporation of Ohio

Application August 14, 1940, Serial No. 94,425

Term of patent 7 years

To all whom it may concern:

Be it known that I, William I. Smith, a citizen of the United States and resident of Goshen, Elkhart County, Indiana, have invented a new, original, and ornamental Design for a Juvenile Swing, of which the following is a specification, reference being had to the accompanying drawings, forming a part thereof.

In the drawings:

Figure 1 is an end elevation of a juvenile swing showing my new design; and

Figure 2 is a side elevation thereof.

I claim:

The ornamental design for a juvenile swing, as shown.

WILLIAM I. SMITH.
